(57) **CLAIM**

The design of the nozzle, as shown and described.

DESCRIPTION

FIG. 1 is a perspective view of the subject nozzle;

FIG. 2 is a perspective view of the subject nozzle from an opposite side;

FIG. 3 is a side view of the subject nozzle;

FIG. 4 is a side view of the subject nozzle from an opposite side;

FIG. 5 is an end view of the subject nozzle;

FIG. 6 is an end view of the subject nozzle from an opposite side;

FIG. 7 is a top view of the nozzle;

FIG. 8 is a bottom view of the nozzle;

FIG. 9 is a cross-sectional view of the nozzle;

FIG. 10 is a view similar to that of FIG. 1, with a cover in place; and,

FIG. 11 is a view similar to that of FIG. 2, with a cover in place.

The broken lines in the drawings depict environmental subject matter only and form no part of the claimed design.
